INVENTOR

BY *Victor J. Evans*

ATTORNEY

G. Jones Jr.
WITNESS:

Patented Dec. 15, 1925.

1,566,140

UNITED STATES PATENT OFFICE.

GEORGE JONES, OF PHILADELPHIA, PENNSYLVANIA.

KNIFE SHARPENER.

Application filed April 4, 1925. Serial No. 20,785.

To all whom it may concern:

Be it known that I, GEORGE JONES, a citizen of the United States, residing at Philadelphia, in the county of Philadelphia and 5 State of Pennsylvania, have invented new and useful Improvements in Knife Sharpeners, of which the following is a specification.

This invention relates to a sharpener 10 particularly designed for use in sharpening carving knives, paring knives, scissors, or the like, and an object of the invention is to provide a sharpener of the rotary disc type which is simple in construction, and 15 may be manufactured at a relatively low cost in proportion to the cost of approved types of rotary disc knife sharpeners now on the market.

Another object of the invention is to provide 20 a sharpener as specified, in which a holder or support is provided being constructed from a single piece of sheet metal and having trunnions struck therefrom on which the rotary discs are rotatably supported, the said discs also being supported 25 for limited lateral movement relative to the supports to permit proper engagement of a knife or scissor blade with the disc to insure proper sharpening of the blade.

30 Other objects of the invention will appear in the following detail description, and in the accompanying drawings wherein:

Figure 1—is a perspective view of the improved sharpener.

35 Figure 2—is a vertical section through the improved sharpener.

Figure 3—is a top plan of the sharpener.

Figure 4—is a plan view of the blank from which the supporting structure is 40 made.

Figure 5—is a detail section through the blank showing it partially formed.

Figure 6—is a perspective view of a modified form of the invention.

45 Figure 7—is a section through the modified form.

Referring more particularly to the drawings, the improved sharpener comprises a carrying plate 1 which is constructed of a sheet metal, and has a perforated attaching base 2 which is adapted to be attached by screws or the like to any suitable support. The blank from which the carrying plate 50 is formed is provided with a centrally disposed slot 3 extending upwardly from the base 2, and it has a pair of tongues 4 one

formed on each of the sections 5 and 6 which are formed by the slot 3. As clearly shown in Figure 3 of the drawings, the section 6 is offset laterally with respect to the section 5 so as to permit overlapping of the inner edges of the discs 7. The discs 7 are constructed of tool steel or any other suitable hardened steel, and have central or axial openings 8 into which the trunnions 65 or bearings 9 are forced to rotatably support the discs. The tongues 4 are bent down against the outer sides of the discs 7 so as to hold the discs on their bearings 9 and prevent lateral displacement of the discs. 70 However, the tongues 4 are spaced sufficiently from the discs and the openings 8 are of sufficient size as to permit limited lateral pivoted movement of the discs so as to allow the perimeters of the discs to be 75 positioned at an acute angle to the direction of travel of a knife blade thereover, so as to provide the proper sharpening action of the blade. As clearly shown in the drawings, the bearings or trunnions 9 are struck 80 from the plate 1, and are retained integrally therewith being connected to the sections 5 and 6 by straps 11 which are left in their original integral connection with the bearings 9. 85

In Figures 6 and 7 of the drawings, a modified form comprises a carrying plate 20 which is provided with a horizontal attaching portion 21 and an upright portion 22. The upright portion 22 has a central slot 23 therein, which when a portion of the upright is bent downwardly over the disc 24, forms an upwardly opening slot which is adapted to receive a scissors blade to permit contact or engagement of the scissors 95 blade with the disc 24 for the purpose of sharpening the scissors blade. The disc 24 is rotatably supported by the bearing or trunnion 25 struck from the upright portion of the carrying plate 20 in the same manner 100 in which the bearings 9 are formed. The edges of the blade receiving opening 26 may be angled as desired, for the purpose of regulating the proper angle of the scissors blade with respect to the rotary sharpening disc 24. It is to be understood that in use, the horizontal portions are to be used for attaching the sharpener to any suitable support. 105

It is, of course, to be understood, that the 110 invention may be constructed in various other manners and the parts associated in

different relations, and therefore, I do not desire to be limited in any manner, except as set forth in the claims hereunto appended.

What I claim is:—

- 5 1. In a sharpener, a carrying plate, rotary sharpening discs, said discs provided with central openings, disc bearings struck from the carrying plate and engaging in said openings for rotatably supporting said discs and tongues connecting the disc bearings and carrying plate.
- 10 2. In a sharpener, a carrying plate, rotary sharpening discs, said discs provided with central openings, disc bearings struck from the carrying plate and engaging in said openings for rotatably supporting said discs, tongues formed integrally with and connecting the disc bearings and carrying plate and tongues formed on said carrying plates and bent downwardly over said discs.
- 15 3. In a sharpener, a carrying plate, rotary sharpening discs, said discs provided with central openings, disc bearings struck from the carrying plate and engaging in said

openings for rotatably supporting said discs, tongues formed integrally with and connecting the disc bearings and carrying plate, said carrying plate having laterally offset portions to permit overlapping of the adjacent portions of said discs.

4. In a sharpener, a carrying plate, rotary sharpening discs, said discs provided with central openings and bearings struck from the carrying plate and engaging in said openings for rotatably supporting said discs, said carrying plate provided with a slot and having the portion on one side of said slot offset laterally with respect to the portion on the other side of the slot whereby said discs may overlap at the portions registering with said slot, tongues formed upon said bearing plate and bent downwardly over said discs to prevent displacement of the discs, said tongues adapted to permit limited lateral displacement of the discs.

In testimony whereof I affix my signature.
GEORGE JONES.
